FOUR-WAY UMBRELLA

Franz Vogel, New York, N. Y.

Application March 16, 1946, Serial No. 654,870

3 Claims. (Cl. 224—5)

1

The present invention relates to improvements in umbrellas and the like and more particularly to means for carrying the umbrella about the person of the user.

Ladies who carry umbrellas in anticipation of but not while it is raining find it a handicap and inconvenience about their persons when engaged on a shopping mission, because of the necessity of holding the same in the hand. In such instances a greater convenience would result if the umbrella were provided with suitable, practical means of hanging it upon the back, shoulder, wrist or arm, thus freeing both hands at the same time. This is the main purpose of the present invention.

One of the objects thereof is to provide a simple, efficient and inexpensive ladies' umbrella which admits of being carried about from place to place portably in a suspended position upon her back, shoulder, wrist or arm in a convenient manner by manipulation of an attaching cord with which the umbrella is provided.

Another object thereof is to provide a type of umbrella wherein use is made of looping an attaching cord either longitudinally of the umbrella to adapt same for suspension upon the shoulder of the user, or else looping said attaching cord at one end of the umbrella to adapt same for girdling around the arm or wrist of the user.

A further object thereof is to provide an attaching cord for the stick of an umbrella, parasol or the like which, at one end thereof, is fixedly secured to the stick, and at the other and opposite end thereof is detachably secured to the stick or to the first-named end of the stick for the purpose of accommodating the cord for suspension upon different parts of the user's person.

A still further object thereof is to provide an attaching cord for a ladies' umbrella or the like adapted to be formed into a loop and suspended from the arm or wrist. In order to protect her arm or wrist from the chafing influence of knots and similar protuberances formed upon the ends of the loop, I provide smooth-faced loop delimiting members which space looped parts of the attaching cord out of contact with her arm or wrist.

With the above and other objects in view, my invention consists in the combination, arrangement and details of construction disclosed in the drawings and specifications and then more particularly pointed out in the appended claims.

In the drawings, wherein similar reference characters designate similar parts throughout the respective views,

2

Figure 1 is a side elevation of an umbrella equipped with my invention.

Figure 2 is a fragmental side elevation thereof showing the attaching cord of Figure 1 formed into a different kind of loop.

Figure 3 is a fragmental detail view, showing the attaching cord of the umbrella formed in still another different kind of loop.

Figure 4 is a longitudinal, fragmental, sectional view of one end of my invention, showing various details thereof.

Figure 5 is a section taken on line 5—5 of Figure 4.

Figure 6 is a fragmental detail view of one end 15 of a prop.

Figure 7 is a side elevation, partly in section, of the other end of the invention.

Figure 8 is a sectional view taken on the line 8—8 of Figure 7.

Figure 9 is a side elevation at right angles to Figure 7, showing the cord end removed from the staff.

In the drawings, which are merely illustrative of my invention, the various parts and details of my invention are shown. The umbrella proper is of conventional design and construction, being accorded a shape and style conforming to prevailing trends. It is important that the umbrella have its stick 10 projecting beyond opposite ends of the distensible cover part of the umbrella, because my invention is adapted to close and conceal these ends by means of suitably shaped props for the purpose of holding the opposite ends of the attaching cord which forms the basis of the present attachment and invention.

These props are broadly designated 11 and 12, and as shown particularly in Figure 1 they are plug-like cylindrical bodies. The prop 11 forms the handle of the umbrella, while the prop 12 forms the tip of same. The collapsed covering of the umbrella is denoted at 13.

One prop, 14, which is the handle of the umbrella is made conveniently out of a plastic material such as lucite, or it may be shaped out of indurated cotton, wood, metal or leather, and configured to any desired outline. It is formed with an integral eye 15 having the opening 16. At the other end of this handle 14 a tubular terminal 18 is formed which may be fluted exteriorly as indicated in Figure 6 at 17a.

The other and opposite prop 19 is made preferably of the same material as handle 14 and is shown as a cylindrical body, which is also formed at one end with an integral eye 20. However, in order to provide means for inserting not only a

portion of the flexible attaching cord into this eye in threaded relation, but also permit insertion of a cord retaining element through this eye, it will be seen from Figure 7, that this plug or prop 19 is chamfered out diametrically and centrally to provide a groove 22 which opens out from opposite sides of the prop. This groove will be made of a depth sufficient to readily accommodate the thickness of the flexible cord 24. This prop 19 is also formed at its inner end with a tubular terminal 23 which may also be fluted exteriorly if desired.

It will be noted that one end of the umbrella stick 10 is snugly fitted into the tubular terminal 18 of the handle 14, while the other end thereof is snugly fitted into tubular terminal 23 of the proper or tip 19. In this way the opposite ends of the umbrella present a finished appearance and pleasing effect.

To these props, 14 and 19 respectively, the attaching cord 24 will be connected. I take a single length of cord, made from silk, leather, cotton or rayon as may be desired, and attach it fixedly at one end to the handle 14 and detachably secure its other end upon the tip 19 of the umbrella.

As is seen from Figure 5, one end of the cord 24 is brought back upon itself foldably and loosely to provide the coaxial strands 25 and 26 respectively. These strands 25 and 26 are formed upon an integral bight portion or loop 27 forming a flexible eye upon this end of the cord. This eye is held against unravelling by a coil of yarn or the like means 28 wound upon both strands 25 and 26 or otherwise. At the point where the returned end of the cord 24 engages the main length of the cord 24, it is treated plastically or otherwise to provide a rigid bearing for a protecting and confining member hereinafter set forth. This bearing end of the cord 24 has a conical surface which tapers as at 29 remotely from the loop 27 so as to point in the direction of the other end of the cord.

Designed to back up against this conical tapering bearing 29 of the looped end of the cord 24 and be limited in movement thereby in one direction, is a confining member 30 of cylindrical cross-section. It presents a smooth surface outside. Here it is formed with a conical tapering formation 32. The side of this member which confronts the loop 27 of cord 24 is formed as a straight surface in a plane at right angles to the axis of the member as at 31. Inside, this member has a tubular bore 33 into which is operatively fitted a tubular body 34 which flares outwardly from its inner end. It will be seen readily that the conical tapering bearing 29 of the cord 24 is adapted to snugly enter this flaring part of the body 34 of the confining member 30 removably. This protects the looped part from coming apart.

The cord 24 is formed with another looped portion at the end opposite to that shown in Figure 5, as shown in Figure 9. The looped portion 27 thereof has been linked fixedly onto the ring or eye 15 of the handle 14. At its free end the cord 24 is designed to have a disengageable connection with the tip end 19 of the umbrella. For this purpose one part of cord 24 is doubled back upon itself to provide the coaxial strands 36, 37 shown in Figure 9, to provide an integral interconnecting loop or eye 38 upon the strands 36, 37. In a manner already described these strands at the point where the returned end of strand 36 is engaged with cord 24, are formed with the conical tapering bearing 29 already explained.

It is proposed to secure to the last mentioned

looped portion 38 of the attaching cord 24 a self-retaining element for the cord which becomes serviceable after the latter is connected to the tip of the umbrella. This is illustrated in Figure 7.

5 This element is a preferably cigar-shaped plastic body or knob designated 39. It is intended to be a cross-piece for one end of the cord.

Specifically the body 39 consists of a plug shaped cylindrically. Centrally this body is formed with oppositely arranged band-like portions 40, 41, with an intervening shank 42 of reduced diameter so as to provide an annular groove 43a of a depth equal to the thickness of the cord. The opposite ends of this element are formed coaxially and taper in opposite directions as at 43, 44. By thus tapering this element is devoid of sharp corners and affords a readily graspable part.

20 The cord 24 is wrapped around so as to be coiled into the groove 43a of this element 39 around reduced shank 42 thereof, for in this manner the cord will be best countersunk into this element, after which the two strands 36, 37 (Figure 9) will, at their inner parts, be affixed together by means of a plastic shell or otherwise to close the loop 38 of the cord in said groove and hold the member 39 against displacement from the cord.

25 It will be seen that the looped portion at one end of the cord, where it is fixedly attached to handle 14 (Figure 5) has a slit 45 necessarily formed between the strands 25, 26 thereof. Similarly between the strands 36, 37 of the looped portion at the other and free end of the cord 24 is a slit 46, shown in Figure 9.

30 35 The use and operation of the present invention will now be detailed.

The purpose is to make the umbrella convenient to carry about one's person. If it is desired to carry the umbrella upon the back so as to carry

40 it about subconsciously, with every mark of assurance that it will not accidentally slip off from the position where placed, then the parts will be arranged as shown in Figure 1. Here one end of the cord is fixedly secured at all times to the handle 14 of the umbrella. The other and free end of the cord, the part which carries the cross-piece 39 is manipulated by slidably seating the two overlapping strands 36, 37 (Figure 9) in the groove 22 of the prop or tip 19, as shown in Figure 8.

45 For this purpose, the cigar-shaped element 39 and the countersunk loop 38 of the cord 24 is slidably passed into and through eye 21 of ring 20 formed on this tip 19, at the same time that the strands 36, 37 of the cord are being moved out of the groove 22. Then by swinging the element 39 around into T-shaped formation with the cord, it serves its function as a cross piece as shown in Figure 1, by engaging the ring 20 with overlapping contact, thus preventing accidental displacement of this end of the cord from the eye 21.

50 55 Figure 1 shows that the cord 24 is bowed longitudinally of the umbrellas in looped relation. This bowed formation enables the cord 24 to be slung over the neck of the wearer so that the cord will extend diagonally across the breast of the user while the umbrellas proper lie across her back. It frees both arms and hands.

50 65 If it is desired to carry the umbrella suspended from the shoulder, the bowed formation of the cord 24 shown in Figure 1 is again relied upon. The cord is now suspended from the handle end of the umbrella in such a manner, that the strands 25, 26 of this looped end of the cord rest, together with the confining member 30, directly

70 75 upon the shoulder, thereby causing the cord itself

to extend downwardly along the arm of the user and positioning the umbrella proper vertically down the side. In this position, the confining member has been frictionally fitted against the conical tapering bearing 29 of the cord, and it provides an extended yet smooth bearing surface for the umbrella upon the shoulder so that a mild clamp like effect is had between the rigid handle 14 of the umbrella and the contiguously adjacent confining member 30. The bowed cord 24 could also be hung from a hook on a wall.

When it is desired to carry the umbrella upon the arm the parts will be arranged as shown in Figure 2. The knob or cross-piece 39 will be disengaged from the position it is shown to have in Figure 1 by being slipped out of the eye 21 of the tip 19, as the cord 24 is being slipped along groove 22. Being now disengaged from the tip 19, the knob 39 is inserted through slit 45 between strands 25, 26 of the cord 24, where it will again serve to prevent accidental displacement of itself therefrom. A loop has not been formed by extending (Figure 2) cord 24 so it forms a bight portion 24a, with its stretch 24b brought back to a position to permit insertion of knob 39 through the mentioned looped part of the cord. The two confining members 30 will now delimit the loop entirely from the remaining parts of the umbrella, and their smooth faces will not chafe the skin of the user with which they may contact. The looped cord is now slipped around the arm so as to girdle the same suspendingly.

When it is desired to carry the umbrella around the wrist the parts are as shown in Figure 3. The loop is formed in exactly the same manner as the loops shown in Figure 2 as far as extending the knob 39 through the looped portion of the cord as indicated hereinbefore, only that before making this insertion of the knob, the cord 24 is manipulated by wrapping portion 24c and an opposite portion 24d around the wrist of the person to form the coil 24e, and then extending the stretch 24b to permit of such insertion of the knob for retaining purposes.

From the foregoing it is seen that the umbrella can be attached at four different places about the person of the user, by making easily and conveniently the change-overs. I do not mean to confine myself to the exact details of construction herein set forth save as pointed out in the appended claims.

While the umbrella has been referred to as a four way type, it will be understood that this is not meant as a term of limitation and that the invention herein disclosed can have other uses, including encircling the waist of the wearer with the cord disclosed in Figure 2. When the cord or belt is wrapped around the waist, the umbrella hangs along the right or left side of the wearer, as the case may be.

What I desire to claim and secure by patent is:

1. In combination an umbrella having an elongated stick, and means for carrying said umbrella consisting of a pair of plugs fitted to opposite ends of said stick, a single length of cord having one end thereof passing through one of the plugs to be brought back in secured relation upon said cord to form a loop, a knob carried by the other end of the cord removably and alternatively engageable with the plug and said cord loop, the other end of said cord engaging about said knob and being returned along the length of the cord defining a second loop and cord confining members engaging about the ends of said cord at the adjacent ends of said loops for setting apart therebetween the limits of a flexible hanger for said body.

2. As a new article of manufacture, an umbrella carrying attachment comprising a length of cord formed at one end with a looped portion secured back upon itself defining a loop at one end thereof, a knob of cylindrical shape having an annular groove thereabout within which the other end of the cord is engaged and retained, and a member formed with a key hole shaped opening through which said knob and cord may be extended and a tubular end on said member for attachment to one end of the umbrella stick.

3. As a new article of manufacture an umbrella carrying attachment comprising a length of cord formed at one end with a looped portion secured back upon itself providing a tapered portion toward the other end of the cord, a retainer fitted over said tapered portion whereby the loop portion is fixedly secured, a second knob of cylindrical shape having an annular central groove into which the other end of the cord is looped and retained, and a member formed with a keyhole-shaped opening through which said cord and said second knob may be retainedly extended, said member being removable and having a remote tubular end for securing to one end of the umbrella stick.

FRANZ VOGEL.
